UNITED STATES PATENT OFFICE.

FREDERICK A. INGALLS, OF BREMEN TOWNSHIP, COOK COUNTY, ILLINOIS, ASSIGNOR
TO WYMAN-GORDON COMPANY, OF WORCESTER, MASSACHUSETTS, A CORPOR-
ATION OF MASSACHUSETTS.

EARTH-BORING APPARATUS AND METHOD OF MAKING SAME.

1,408,886.

Specification of Letters Patent.

Patented Mar. 7, 1922.

Application filed July 29, 1921. Serial No. 488,294.

To all whom it may concern:

Be it known that I, FREDERICK A. INGALLS, a citizen of the United States, residing in the township of Bremen, county of Cook, 5 and State of Illinois, have invented certain new and useful Improvements in Earth-Boring Apparatus and Methods of Making Same, of which the following is a specification.

10 This invention relates to earth-boring apparatus and method of making the same, but more particularly to drill jars for use in sinking deep wells, and has for its primary object to economically produce a device of this class which will be durable and 15 efficient in service.

Further objects of the invention are to provide uniformity in the physical characteristics of the steel throughout; to eliminate distortion; to eliminate welding; to permit the use of a higher quality of steel than is possible where welding is necessary; to provide a jar construction which may be produced practically entirely by forging; 25 and to provide a structure which may be quickly and easily assembled and when once assembled cannot become disassembled or work loose.

The many other objects and advantages of 30 my invention will be better understood by reference to the following specification, when considered in connection with the accompanying drawings illustrating a selected embodiment thereof, in which—

35 Fig. 1 is an elevation of the reins of the upper jar member at the completion of the initial forging operation.

Fig. 2 is the same as Fig. 1, plan view.

40 Fig. 3 is an end view of one of the reins of the jar member shown in Fig. 1.

Fig. 4 is a plan view of the head, to which the reins, shown in Fig. 1, are to be attached.

Figs. 5, 6 and 7 are sections on the lines 5—5, 6—6 and 7—7 respectively, of Fig. 4.

45 Fig. 8 is an elevation of the lower jar member which links with the upper member shown in the previous figures.

Fig. 9 is an elevation of the lower jar member and the reins of the upper member, 50 illustrating the mode of assembly.

Fig. 10 is an elevation, partially in section, of the assembled and completed jar.

Figs. 11 and 12 are sections on the lines 11—11 and 12—12 respectively, of Fig. 10.

Referring to the drawings, the jar consists of two members, 15 and 16, which will be hereinafter referred to as the upper and lower jar members respectively, though it will be readily appreciated that the relative positions of these members may be reversed. 55 These members are substantially identical in form when completed and assembled with the exception that the upper member is usually provided with a tang 17 for attachment to the operating rod whereas the lower member has a socket 18 to receive the boring tool. 60 These members interlink in substantially the same manner as the links of a chain.

The upper jar member 15 is formed in 70 two parts, the reins 19 and the head 20. The reins 19 are joined at their outer end portion by a web 21. The inner end portions of the reins are provided with oppositely disposed inwardly projecting lugs 22 75 which are adapted to be forced into opposite ends of socket 23 extending transversely through the outer end portion or shank of the head 20. These lugs are preferably formed slightly flaring and the socket is 80 initially of sufficient size to admit the enlarged outer ends. The compression of the head in the assembling operation causes the socket to be contracted to tightly fit these flaring lugs and to form an absolutely rigid 85 union between the reins and the head. The grip of the socket upon the lugs is further increased by the shrinkage of the heated head in cooling, the lugs being cold at the time of assembly. 90

The inner faces of the reins 19 are preferably cut away about the lugs 22 in order to form a seat 24 for the shank 25 of the head 20 as it is advisable to form this shank of greater thickness than the width of the 95 slot 26 to provide adequate strength and stability. The end or striking face 28 of the shank 25 is preferably concaved to fit the rounded end 29 of the lower member 16. This concavity of the striking face tends to 100 force the metal of the tip inwardly and thus prevents the burring of the tip during the boring operation.

The lower member 16 is preferably formed in one part with the reins integral 105 with the head. The corresponding slots 26 and 32 in the upper and the lower jar members respectively, should preferably be of

equal length as should the reins of these members so that when the two members are pressed together in service, the tips 33 and 29 will simultaneously contact with the opposing striking faces 34 and 28 respectively. The pressure exerted by the upper member upon the lower member is thus divided between the two tips.

The jar is preferably formed practically entirely by forging and no welding is necessary. This elimination of welding is a particularly important feature as it permits the use of a higher grade of steel than would be possible if welding was required.

15 Furthermore, the welded joints have always been the weak points of the jar. The use of a higher grade of steel enables the length of stroke or relative movement of the jar members to be safely increased and thus increases the force of the jolt. This accomplishes a very material saving of time in the drilling operation.

In the forging operation the reins are initially formed from a blank by means of forming dies and trimmed between trimming dies into the form shown in Fig. 1. The reins are preferably partially spread in the manner shown in order to facilitate the operation of the trimming dies in removing the flash. The reins are then still further spread into the form indicated in Fig. 9 to facilitate the interlinking of the lower jar member therewith. Each of the reins should preferably be heated at the 30 bending point 38. The lower jar member 16 is forged complete between forming dies and then trimmed between trimming dies into the form shown in Fig. 8. In order to permit the interlinking of the two members 35 in the manner shown in Fig. 9, the portions 39 of the reins between the web and the head are spread into substantially the form indicated by the dotted lines in Fig. 8.

As soon as the lower jaw member is 40 brought into alignment with the center line of the reins of the upper member, these reins are ready for assembly with the head 20. This assembly is accomplished by placing the shank of the head between the spread 45 ends of the reins 19 with the lugs 22 disposed opposite their corresponding ends of the socket 23. The head at this time is preferably in a heated condition, whereas the reins are cold except at the bending 50 points 38. The reins 19 are now struck between dies to force their ends inwardly and the lugs 22 into socket 23. These dies compress the head and cause the socket to be contracted to closely fit the flaring lugs. 55 The subsequent shrinkage of the heated head in cooling causes an extremely tight binding pressure to be exerted by the walls of the socket upon the unheated lugs so that subsequent loosening of the lugs within 60 the socket or their withdrawal therefrom 65

is rendered impossible. The union thus formed between the reins 19 and the head 20 is substantially as strong as though the upper jar member had been initially formed in one part like the lower jar member and the jar at the joint is stronger than any of the reins. The assembled jar is then turned a right angle and struck between dies to straighten the warped portions 39 of the reins of the lower member.

75 The jar members are maintained in alignment during the drilling operation by the guides 40 and 41 on the upper and lower jar members respectively. The threading of the tang 17 and the socket is performed 80 after the completion of the forging and assembling operations.

It will thus be readily evident that a strong and durable jar has been provided. This is particularly important in drilling 85 deep wells for the breakage of a jar will often seriously delay the drilling operation and may necessitate the abandonment of the well. Heretofore it has been generally accepted that a jar could not be used 90 more than a thousand feet, but with the present jar any practical depth may be reached with a single jar. In addition to the loss of time and labor resulting from a broken or worn out jar, these jars are expensive and the cost of the operation is 95 very materially increased if it is necessary to provide a number of new jars to drill a single well.

I am aware that many changes may be 100 made in the form and method of production of my improved jar, without departing from the spirit of my invention, and I reserve the right to make all such as fairly fall within the scope of the following claims.

105 I claim as my invention:

1. A jar link comprising spaced reins connected at substantially their outer ends and having inwardly projecting lugs near their inner ends, and a head provided with sockets to receive and engage the corresponding lugs on said reins to form a connection between said reins and said head.

2. A jar link comprising substantially parallel spaced reins connected at their outer ends by a web and having oppositely disposed inwardly projecting lugs near their inner ends, and a head provided with sockets to receive and engage said lugs to form a connection between said reins and said head.

3. A jar link comprising spaced reins connected at substantially their outer ends and having inwardly projecting flaring lugs near their inner ends, and a head provided with a socket to receive and engage said lugs to 125 form a connection between said reins and said head.

4. A jar link comprising spaced reins connected at substantially their outer ends and having inwardly projecting lugs near their 130

inner ends, and a head having a shank disposed between the inner ends of said reins and sockets formed in the opposite sides of said shank to receive the corresponding lugs 5 on said reins.

5. A jar link comprising spaced reins connected at one end and having recesses formed in their inner faces at their opposite ends, lugs projecting inwardly from the recessed 10 portions of said reins, and a head provided with a shank fitting in the socket formed by the recesses in said reins and having sockets in its opposite faces to receive and engage the corresponding lugs on said reins to form 15 a connection between said head and said reins.

6. A jar link comprising a head, reins connected at their outer ends and separated at their inner ends, and means for attaching 20 the inner ends of said reins to said head.

7. A jar link comprising a head, reins connected at their outer ends and separate at their inner ends, and means for providing an interlocking connection between the inner 25 ends of said reins and said head.

8. A jar link comprising a head, reins connected at their outer ends and separate at their inner ends, and lugs on the inner end portion of each of said reins fitting within 30 corresponding sockets in said head to form an interlocking connection between said reins and said head.

9. A jar link comprising two sections having interlocked parts forged into engagement. 35

10. The method of making jar links consisting in forming the link in two sections having interlocking parts and forging these parts into engagement.

11. The method of making jar links consisting in forming the reins with laterally projecting lugs, forming the head with sockets to receive the corresponding lugs on the reins, and forcing the lugs on the reins into the sockets in the head to form an interlocking joint between the head and the reins. 40

12. The method of making jar links consisting in forming the reins with laterally projecting lugs, forming the head with sockets to receive the corresponding lugs on the 50 reins, forcing the lugs on the reins into the sockets in the head, and compressing the head to retain the lugs within the sockets.

13. The method of making jar links consisting in forming the reins with inwardly 55 projecting lugs, forming the head with lateral sockets to receive the corresponding lugs on the reins, placing the head in a heated condition between the unheated lugs, and forcing the lugs into the sockets in the head. 60

14. The method of making jar links consisting in forming the reins with inwardly projecting lugs, forming the head with lateral sockets to receive the corresponding lugs on the reins, placing the head in a heated 65 condition between the unheated lugs, forcing the lugs into the sockets in the head, and compressing the head to contract the sockets about the lugs.

FREDERICK A. INGALLS.
